CLAIM

The ornamental design for a mobile telephone, as shown and described.

DESCRIPTION

FIG. 1 is a front view of a mobile telephone.

FIG. 2 is a top view of the mobile telephone of FIG. 1.

FIG. 3 is a left side view of the mobile telephone of FIG. 1.

FIG. 4 is a right side view of the mobile telephone of FIG. 1.

FIG. 5 is a bottom view of the mobile telephone of FIG. 1.

FIG. 6 is a rear view of the mobile telephone of FIG. 1.

FIG. 7 is a left side view of the mobile telephone of FIG. 1 in an open position; and,

FIG. 8 is a front view of the mobile telephone of FIG. 1 in an open position.

The broken line showings are for illustrative purposes only and form no part of the claimed design. The outermost broken lines that are adjacent to the claimed surfaces form the boundaries of the claimed design.
